US0D1082242S

(12) United States Design Patent (10) Patent No.: US D1,082,242 S
(45) Date of Patent: * Jul. 8, 2025

(54) SANDAL

(71) Applicant: Birkenstock IP GmbH, Linz am Rhein (DE)

(72) Inventors: Arno Marchand, Linz am Rhein (DE); Parthasarathee Behura, Linz am Rhein (DE)

(73) Assignee: Birkenstock IP GmbH, Linz am Rhein (DE)

() Term: 15 Years

(21) Appl. No.: 29/961,393

(22) Filed: Sep. 5, 2024

Related U.S. Application Data

(62) Division of application No. 35/518,623, filed on Sep. 13, 2023 (U.S. filing date under 35 U.S.C. 384), and having an international filing date of Sep. 13, 2023, now Pat. No. Des. 1,062,168.

CLAIM

The ornamental design for a sandal as shown and described.

DESCRIPTION

FIG. 1 is a right side view of a sandal showing our new design;

FIG. 2 is a top view thereof;

FIG. 3 is a left side view thereof;

FIG. 4 is a perspective view thereof;

FIG. 5 is a front view thereof;

FIG. 6 is a back view thereof;

FIG. 7 is a bottom view thereof;

FIG. 8 is a right side view of another embodiment;

FIG. 9 is a top view thereof;

FIG. 10 is a left side view thereof;

FIG. 11 is a perspective view thereof;

FIG. 12 is a back view thereof;

FIG. 13 is a bottom view thereof; and,

FIG. 14 is a front view thereof.
